W., T. W. H. & P. C. PHILIPSON.
LIFE GUARD FOR TRAM CARS AND OTHER VEHICLES.
APPLICATION FILED APR. 25, 1913.

1,068,363.

Patented July 22, 1913.

Witnesses T. G. Hanway L. M. Murrell

A technical drawing of a mechanical assembly. It features a central vertical rod with a horizontal slot. A small circular component is positioned within this slot. A horizontal bar, labeled '14' at its top, is attached to the right side of the central rod. A vertical line, labeled '16' at its top, extends downwards from the central rod. A horizontal line, labeled '22' at its right end, extends to the left from the central rod. A horizontal line, labeled '18' at its left end, extends to the right from the central rod. A dashed line labeled '2' is also present.

UNITED STATES PATENT OFFICE.

WILLIAM PHILIPSON, THOMAS WHITTLE HOPWOOD PHILIPSON, AND PERCY CLARKSON PHILIPSON, OF BOLTON, ENGLAND.

LIFE-GUARD FOR TRAM-CARS AND OTHER VEHICLES.

1,068,363.

Specification of Letters Patent.

Patented July 22, 1913.

Application filed April 25, 1913. Serial No. 763,630.

To all whom it may concern:

Be it known that we, WILLIAM PHILIPSON, THOMAS WHITTLE HOPWOOD PHILIPSON, and PERCY CLARKSON PHILIPSON, subjects of the

5 King of Great Britain, and residents of Holland Street Works, Astley Bridge, Bolton, in the county of Lancaster, England, have invented a certain new and useful Improvement in Life-Guards for Tram-Cars 10 and other Vehicles, of which the following description, together with the accompanying sheet of drawings, is a specification.

This invention relates to those guards which are mounted at the sides of the 15 vehicle, generally in combination with life guards of the "gate" or "cradle" type.

It is well known that a certain space intervenes between the front gate or trigger and the cage, cradle or receptacle mounted 20 behind the same for gathering or receiving any obstruction which strikes the front gate, and the guards forming the subject of this present invention are employed to guard such spaces and prevent any person from 25 falling at this part beneath the vehicle. In many forms of cars where the body thereof becomes lowered through the wearing of the wheels or through other reasons, these side guards occupy a position closer to the 30 ground than is desirable, and in many cases where the body of the tramcar oscillates to a great extent these side guards come into contact with the ground and are thereby damaged.

35 Our present invention consists in so constructing these guards or parts thereof that should they strike the ground they are enabled to rise or move on their bearings so as to prevent any damage being done thereto.

In the accompanying sheet of drawings which are illustrative of our said invention: Figure 1 is a side elevation of a portion of a tramcar having our improvements applied 45 thereto. Fig. 2 is a similar view to Fig. 1 but shows certain portions of the guard in different relative positions. Fig. 3 is also a similar view to Fig. 1 and shows the parts in further different relative positions. Fig. 50 4 is an end elevation of certain of the parts illustrated by Fig. 1.

Similar letters and figures of reference indicate like parts throughout the several views.

55 The type of life guard to which this in-

vention relates is that wherein a front gate or trigger 1 is employed, working through suitable connections, in conjunction with the cage or receptacle 2 as shown in dotted lines by Fig. 1, these parts forming no portion 60 whatever of our said invention. Fulcrumed at 3, 4 in bearings 5, 6, at any suitable position on the body of the car A are downwardly extending levers 7, 8, and upon these levers are mounted loosely on pins 9, one, 65 two or more laths or cross bars 10. The lowest bar 12 however we mount upon strips, levers or links 13, 14 which are provided with slots 15, 16 slidable upon pins or studs 17, 18, fixed upon the downwardly 70 extending levers 7 and 8, so that should this lower bar or rod 12 come into contact with the ground or track it will be enabled to move upwardly into the position shown by Fig. 2, thus avoiding any damage that would 75 otherwise be caused by the oscillations of the car. Should the lower front part of the guard come into contact with any obstruction in the ordinary way this lowermost bar or rail will move into the position shown by 80 Fig. 2, and afterward the whole guard and its levers 7, 8, will move on the fulcrums of these latter in the usual manner as shown by Fig. 3, in order to pass over said obstruction or body to enable it to be gathered or 85 picked up by the cradle 2.

A lever 21 is employed in connection with our improved guard, this part being for contacting with any obstruction or body lying in the path of motion of said guard. It is 90 pivoted upon one of the laths 10, so that it will move the other lath into the position shown by Fig. 3. It is provided with a smooth front surface so as not to injure any person with whom it may come into contact. 95

In the accompanying drawings it will be seen that our improved gate is shown in connection with only one side of a tramcar; however, it will readily be understood that we employ these side guards on one or both 100 sides of the vehicle, both at the front and rear parts of same or other desired part.

We claim:

1. In a guard for tramcars and other vehicles, a fender comprising normally vertical bars pivoted to the car, normally horizontal bars crossing the vertical bars and pivoted thereto at the intersections, auxiliary strips secured to and slidable longitudinally of the vertical bars and an auxil- 105 110

iary horizontal bar pivoted to the slidable strips.

- 5 2. In a guard for tramcars and other vehicles, vertical bars pivoted to the car, horizontal bars pivoted to the vertical bars at their intersections, an auxiliary bar carried by and movable longitudinally of the vertical bars, and a lever pivoted to one of the horizontal bars and slidably movable relative to the other bars.

In testimony whereof we have hereunto affixed our signatures in presence of two witnesses.

WILLIAM PHILIPSON.

THOMAS WHITTLE HOPWOOD PHILIPSON.

PERCY CLARKSON PHILIPSON.
